CLAIM

The ornamental design for a perfume bottle, substantially as shown and described.

DESCRIPTION

FIG. 1 is a perspective view of a perfume bottle showing my new design;

FIG. 2 is a side elevational view, the opposite side being the same in appearance as the side shown except that the threads on the top are complete as shown in FIG. 3; FIG. 3 is an end elevational view, the opposite end being the same in appearance as the end shown; FIG. 4 is a top plan view; and FIG. 5 is a bottom plan view thereof.

FIG. 1

FIG. 4
